CLEAR LIQUID DETERGENT COMPOSITION

William C. Krumrei, Springdale, Bruce Strain, Wyoming, and Haskell J. Peddicord, Colerain Township, Hamilton County, Ohio, assignors to The Procter & Gamble Company, Cincinnati, Ohio, a corporation of Ohio

No Drawing. Application June 29, 1956
Serial No. 594,696

8 Claims. (Cl. 252—137)

This invention is directed at the provision of liquid heavy duty detergent compositions which contain large amounts of pyro- or tripolyphosphate together with sufficient silicate to protect against tarnishing or corrosion of aluminum to an objectionable degree, and which are highly resistant to clouding and separation at low temperatures.

The corrosion inhibitor most effective in inhibiting corrosion of aluminum by alkaline phosphates is silicate of soda. In the compositions of the prior art, the addition of silicate of soda to an aqueous solution of an anionic synthetic detergent and an alkaline phosphate caused a separation, cloudiness, or "livering." This is described in U. S. Letters Patent 2,618,607, issued November 18, 1952, to Herbert L. Sanders.

Most anionic synthetic detergents are not, unassisted, completely soluble in aqueous phosphate solutions of a concentration of 18% or more, even in the absence of silicate. The anionics "salt out," forming a gummy layer at the top of the solution or a two phase system. Complete solution of anionic synthetic detergent in such phosphate solutions can be achieved, however, with a solubilizer, usually a sodium salt of the sulfonates of benzene or methyl substituted benzene. If one adds silicate of soda, in amounts adequate to inhibit corrosion of aluminum during the use of the composition in cleansing operations, to those previously known phosphate solutions into which an anionic synthetic detergent has been thus solubilized, the silicate will not dissolve completely, but forms a gelatinous mass or a two phase system.

One of the present inventors has found, as described in the co-pending application of W. C. Krumrei, entitled "Detergent Composition," Serial No. 594,676, filed June 29, 1956, that a specific anionic synthetic detergent in aqueous liquid heavy duty detergent formulations has the property of solubilizing an alkali metal silicate in amounts adequate to inhibit corrosion by phosphates. Silicate of soda is preferred but potassium silicate may be used. The specific anionic synthetic detergent is a water soluble alkyl glyceryl ether sulfonate in which the alkyl radical is derived at least 50% from alcohols of 10 to 14 carbon atoms.

A typical composition embodying this prior discovery may contain from about 6% to about 15% of salts of alkyl glyceryl ether sulfonate, 12% to 27% of potassium pyrophosphate, or potassium tripolyphosphate, 2% to 6% of ethyl or isopropyl alcohol, or diethylene glycol monobutyl ether, 3.5% to 6% of silicate of soda (solids basis) of $\text{SiO}_2:\text{Na}_2\text{O}$ ratio of 1.6:1 to 2.6:1, 3.0% to 8% of a solubilizing agent, and water to make 100%. This produces a clear solution at room temperature and remains clear down to about 50° F.

The alkyl glyceryl ether sulfonate used in both the prior discovery and in the present invention contains about 15% of diglyceryl ether sulfonates. This is only because of the ease of manufacturing this species. The

2

invention may be carried out with alkyl glyceryl ether sulfonates, where the alkyl is at least 50% radicals of alcohols of 10 to 14 carbons, with only monoglyceryl radicals present or with up to about 30% of diglyceryl radicals present. The term alkyl glyceryl ether sulfonate as used herein means any and all of the alkyl glyceryl ether sulfonates from those containing only monoglyceryl radicals to those containing up to 30% diglyceryl radicals.

10 The preferred alkyl glyceryl ether sulfonate is made by reacting an alcohol or alcohol mixtures, containing at least 50% of alkyl radicals of alcohols of 10 to 14 carbon atoms, with from 100% to 130% of the theoretically required amount of epichlorohydrin. The alkyl chloroglyceryl ethers formed by the reaction of this alcohol and epichlorohydrin are converted to glycidyl ethers by heating with a caustic soda solution. The glycidyl ethers thus formed are sulfonated with an alkali metal bisulfite. This results in a content of alkali metal chlorides and sulfates of under 6% of the alkyl glyceryl ether alkali metal sulfonate. Low electrolyte also may be attained by purifying the conventionally Streckerized chloroethers.

Instead of the fatty alcohols used to prepare the alkyl glyceryl ether sulfonate there may be used the alcohols prepared by the "oxo" reaction from straight chain olefins. These should meet the same qualifications as to chain length as the fatty alcohols, that is, these should contain at least 50% of alcohols of 10 to 14 carbons.

25 A number of solubilizing agents are useful in effecting complete solution of synthetic detergents in relatively concentrated electrolyte systems. Trialkyl phosphates, where the alkyl is of low molecular weight, such as triamyl phosphate, or other trialkylphosphates where the 30 sum of the carbons in the alkyl groups are not more than 15, are effective. The alkali metal salts of various organic sulfonates have been used for their solubilizing properties. Petroleum sulfonate salts, salts of benzene sulfonate and methyl substituted benzene sulfonate are 35 among the best of these. The manner in which the anionics solubilize is presented in Schwartz and Perry, "Surface Active Agents," page 307 et seq., Interscience Publishers, New York, 1949.

40 Generically speaking the solubilizers found useful in 45 the present invention are anionic surface active materials, the molecules of which contain both a hydrophobic hydrocarbon portion and a hydrophilic portion. The hydrophobic hydrocarbon portion of the molecule, if a straight chain configuration, may contain from one to three separate alkyl groups each containing not more than 5 carbon atoms. If of cyclic configuration, the hydrophobic hydrocarbon portion of the molecule may contain only one alkyl-substituted or unsubstituted cyclic 50 group containing a total of not more than 8 carbon atoms. The hydrophilic portion of the molecule may be either the water soluble salt of a sulfonic acid radical (sulfonate) or a phosphate. It is to be understood that 55 wherever hereinafter and in the claims the term "anionic solubilizer" appears a material coming within the scope 60 of the above definition is intended.

The solubilizer we prefer is sodium toluene sulfonate. Sodium benzene sulfonate and sodium xylene sulfonate are also effective but require slightly larger amounts to 65 effect blending. The present invention is based upon our discovery that the chill test—or resistance to clouding and separation at low temperatures—of the prior compositions described above is greatly improved by the addition of a second anionic synthetic detergent to the 70 composition. If the alkyl glyceryl ether sulfonate is present in greater amounts than about 8% of the total composition, this addition will be in the nature of a

substitution, the alkyl glyceryl ether sulfonate being reduced to about 8% to allow of the addition of the second anionic. If the alkyl glyceryl ether sulfonate is present in amounts of about 8% or less the second anionic may be added without reducing the alkyl glyceryl ether sulfonate.

The sum of the two anionic synthetics is preferably not more than about 14%. Thus, if the alkyl glyceryl ether sulfonate is at 8%, the second anionic can be 6%.

If it is desired to have the second anionic at a higher level than 6% the alkyl glyceryl ether sulfonate should be reduced accordingly, for instance 4% alkyl glyceryl ether sulfonate and 9% of the second anionic is a satisfactory combination. The second anionic will normally be present in the amounts from $\frac{1}{4}$ to 6 times (6:1 ratio) the amount of the alkyl glyceryl ether sulfonate, the sum of the two being not over about 14%. The remainder will be alkyl glyceryl ether sulfonate.

When these second anionics are used a coconut alkylol amide can be used to enhance sudsing.

Example I

The composition has the formula:

	Parts by wt.
Potassium alkyl glyceryl ether sulfonate containing 66% of radicals from dodecyl alcohol, the remainder being alcohols of 10, 14 and 16 carbons	8
Sodium alkyl benzene sulfonate, the alkyl being polypropylene averaging about 12 carbons	5
Potassium pyrophosphate	20
Coconut monoethanolamide	1
Ethyl alcohol	4
Sodium toluene sulfonate	4
Sodium silicate solids of $\text{SiO}_2/\text{Na}_2\text{O}$ ratio of 2.0:1	4
Water	54

49 parts of water were heated to about 135° F. This temperature was maintained during the addition of the ingredients. The potassium alkyl glyceryl ether sulfonate and the sodium alkyl benzene sulfonate were dissolved therein. The potassium pyrophosphate was added and dispersed in the solution of the anionics. Sodium silicate solution containing 4 parts of silicate solids and 5 parts of water was added. The coconut monoethanolamide was dissolved in the alcohol and the solution was cooled to room temperature. The sodium toluene sulfonate was added with thorough stirring. It was a clear liquid with good heavy duty detergent qualities. It did not separate when cooled to any temperature above 40° F. The ethyl alcohol in this formula may be replaced by isopropanol and equal effects obtained.

This formulation will allow of a moderate amount of variation. The alkyl glyceryl ether sulfonate can be varied between 2 and 9 parts, the alkyl benzene sulfonate between 10 and 5 parts, the pyrophosphate between 18 and 22 parts, the alcohol between 3 and 5 parts, the amide from 1 to 3 parts, the silicate (solids basis) between 3.5 and 6 parts and the sodium toluene sulfonate between 2.5 and 9 parts, with water to make 100 parts.

Example II

The potassium alkyl glyceryl ether sulfonate was identical with that of Example I. The second anionic used was the mixture of potassium salts of the sulfuric acid esters of the product of the reaction of 3 moles of ethylene oxide with 1 mole of middle cut coconut alcohols, containing 66% dodecyl alcohol, the remainder of the alcohols being largely 14 and 16 carbons. This second anionic will for convenience be called alkyl (EtO) sulfate. The composition of this example was as follows.

	Parts by wt.
Potassium alkyl glyceryl ether sulfonate, containing 66% of radicals from dodecyl alcohol the remainder being alcohols of 10, 14 and 16 carbons	8
Potassium alkyl (EtO) ₃ sulfate (defined above)	4
Potassium pyrophosphate	20
Coconut monoethanolamide	1
Ethyl alcohol	4
Sodium silicate solids of ratio $\text{SiO}_2/\text{Na}_2\text{O}$ of 2.0:1	4
Sodium toluene sulfonate	6
Water	53

This composition was prepared by taking 48 parts of water and heating it to about 135° F. The temperature was maintained at about this point throughout the preparation. The potassium alkyl glyceryl ether sulfonate and the potassium alkyl (EtO)₃ sulfate were dissolved in the heated water. The potassium pyrophosphate was added and dispersed. Sodium silicate solution containing 4 parts of silicate solids and 5 parts of water was added. The coconut ethanolamide was dissolved in the alcohol and added. Then the sodium toluene sulfonate was added and the mixture well stirred to achieve blending. The clear solution was then cooled to room temperature. It had good heavy duty detergent properties and did not separate when cooled to 50° F. but began to cloud at about 40° F.

This formula will allow of a moderate degree of variation. The alkyl glyceryl ether sulfonate may vary between 2 and 8 parts, the alkyl (EtO)₃ sulfate from 3.5 to 4.5 parts, the pyrophosphate from 18 to 22 parts, the alcohol from 4 to 5 parts, the amide from 1 to 2.5 parts, the silicate solids from 3.5 to 5 parts and the sodium toluene sulfonate from 5 to 8 parts with water to make 100 parts. There may be substituted for the potassium (EtO)₃ sulfate the sodium or potassium salts of the sulfated product of the reaction of 4 moles of ethylene oxide with 1 mole of nonylphenol.

Example III

The composition contained the following—all parts by weight:

	Parts by wt.
Potassium alkyl glyceryl ether sulfonate, containing 66% of radicals from dodecyl alcohol the remainder being alcohols of 10, 14 and 16 carbons	8
Potassium alkyl (EtO) ₃ sulfate, the same as in Example II	4
Potassium pyrophosphate	20
Sodium silicate solids of ratio $\text{SiO}_2/\text{Na}_2\text{O}$ of 2:1	4
Coconut monoethanolamide	1
Sodium toluene sulfonate	6
Water	57

This was prepared by taking 51 parts of water and heating it to about 135° F. The temperature was maintained at about this point during the preparation of this example.

The potassium alkyl glyceryl sulfonate and the potassium alkyl (EtO)₃ sulfate were added and dissolved by stirring. The potassium pyrophosphate was added and stirred. The silicate, containing 5 parts of water, and the amide were added and stirred. The sodium toluene sulfonate was added and stirred to blend the mixture. Upon cooling to room temperature a clear solution was obtained. This had good sudsing and detergent properties. The viscosity and chill resistance can be improved by the substitution of assistant solubilizers such as ethyl or isopropyl alcohol or diethylene glycol monobutyl ether for a portion of the water.

Example IV

Potassium tripolyphosphate may be used in place of potassium pyrophosphate. A formula was prepared containing:

	Parts by wt.
Potassium alkyl glyceryl ether sulfonate, containing 66% of radicals from dodecyl alcohol, the remainder being alcohols of 10, 14 and 16 carbons	8
Sodium alkyl benzene sulfonate, the alkyl being polypropylene averaging about 12 carbons	5
Coconut monoethanolamide	1
Potassium tripolyphosphate	14
Sodium silicate of soda solids of $\text{SiO}_2/\text{Na}_2\text{O}$ ratio of 1.6:1 to 2.6:1	4
Ethyl alcohol	4
Sodium toluene sulfonate	4
Water	60

55 parts of water were heated to about 135° F. and the ingredients added as shown in Example II, the alkyl benzene sulfonate taking the place of the alkyl (EtO)₃ sulfate. Five parts of water were added with the silicate solids to make the 60 parts shown in the formula.

This was a clear solution, not clouding or settling out at 50° F., but tending to cloud at about 40° F. The ethyl alcohol in this formula may be replaced by diethylene glycol monobutyl ether and equal results obtained.

The temperature of mixing need not be maintained at the 135° F. shown. 110° F. to 140° F. is preferred but somewhat higher or lower temperatures are not objectionable.

It is obvious that the builder need not be a single phosphate, a mixture of potassium pyrophosphate and potassium tripolyphosphate can be used.

Example V

	Parts by wt.
Alkyl glyceryl ether sulfonate—the same as in Example IV	4
Alkyl benzene sulfonate, the alkyl being polypropylene averaging about 12 carbons. Two-thirds of this was potassium salt and one-third sodium salt	35
Potassium toluene sulfonate	9
Ethyl alcohol	8.5
Potassium pyrophosphate	4
Coconut monoethanolamide	18
Sodium silicate solids of $\text{SiO}_2/\text{Na}_2\text{O}$ ratio of 1.6	3
Triethanolamine	4.25
Corrosion inhibitors, substantive fluorescers, dyes and perfume	1.0
Water to make 100 parts (5.3 parts water in 4.25 silicate solids)	46.95

This was prepared by heating 41.65 parts of water to about 135° F. and the ingredients added with good stirring, in the following order. The alkyl glyceryl ether sulfonate and the alkyl benzene sulfonate; the potassium toluene sulfonate; the alcohol in which was dissolved the amide and the substantive fluorescers; the potassium pyrophosphate; the triethanolamine; the silicates, the inhibitors. After cooling, the perfume and color was added.

The order of addition is not critical, it can be varied. There is one point, however, that should be observed—the silicate should go into the mixture after the phosphate. The relatively high alkalinity of the phosphate is needed to keep the silicate from jelling. This composition had good detergent qualities and was clear down to about 40° F.

If alkyl glyceryl ether sulfonate is not used in the formulations of the above examples, all of the synthetic detergent being the second anionic, a clear single phase solution is not attained. If, for instance, alkyl benzene sulfonate, where the alkyl is polypropylene averaging about 12 carbons, is the sole anionic used in these formulations, the addition of alcohol causes two clear layers to form, but they will not blend into a single phase solution, upon the addition of a solubilizer. If an alkyl (EtO)₃ sulfate, where the alkyl is middle cut coconut

alcohol containing about 65% of radicals from dodecanoic acid is used as the sole anionic, the same phenomenon occurs.

A convenient test for clarity may be made by placing the preparation in a test tube 20 mm. diameter and 150 mm. long and holding for five days at some selected temperature below room temperature. In this test highly satisfactory compositions will not cause the alkyl glyceryl ether sulfonate to salt in a viscous or jell-like layer at the top, nor separate into two layers. The detergent of the present invention rates as highly satisfactory at room temperatures down to about 40° F., whereas the preparations with alkyl glyceryl ether sulfonate as the sole anionic will withstand temperatures down to about 50° F. only.

15 Ordinary visual observation in good light, as looking toward a window is used to determine the state of the preparation.

The examples show how the basic discovery—that a mixture of alkyl glyceryl ether sulfonate and a second anionic will solubilize silicate in phosphate solutions—may be used to prepare liquid heavy duty synthetic detergents which remain clear when cooled down to about 40° F. These preparations retain practically all of the other advantages of straight alkyl glyceryl ether sulfonate liquid detergents, particularly the dispersal of soil, thus minimizing redeposition of soil upon the clothes.

It will be noted that alkyl benzene sulfonate is used as the sodium salt and the alkyl (EtO)₃ sulfate as the potassium salt. These salts are preferred because each is the more soluble salt of the respective anionic synthetic detergent. There is required in these formulations some control of the mole ratio of potassium to sodium to prevent crystal formations; also, a maximum sodium ion concentration of about 1.9% of the total composition is the upper limit to prevent sodium pyrophosphate crystals from forming. When the second anionic is used as the sodium salt, with the silicate and solubilizer as sodium salts, the mole ratio of potassium to sodium is about 3.4 to 1. Where all of the composition, except the silicate, is present as potassium salts—the silicate being sodium—the mole ratio of potassium to sodium is about 6.9 to 1. The preferred molar ratios of potassium to sodium are then from about 3 to 1, to 7 to 1.

50 The alkylol amides added as suds builders can be made from the fatty acids of any of the oils of the coconut group comprising coconut oil, palm kernel oil, babassu oil and oils of other members of the tropical palm group that contain at least 50% of lauric and myristic acids. They can also be made from middle cut fractions of the fatty acids of these oils that have their lauric content raised by distillation. If high sudsing is not required the amides may be omitted from the compositions, but with some sacrifice in sudsing power.

55 The silicate and the alkali toluene sulfonate can be added as the sodium salts. Some sodium ions are desirable, although a heavy duty liquid synthetic detergent may be formulated with all of the cations potassium. The preferred formulation will have at least the silicate present as the sodium salt.

60 It will be understood that coloring matter, fabric substantive fluorescent dyes and tarnish inhibitors may be added at any convenient point in the mixing of the composition, and that perfume may be added after the composition has been prepared and cooled.

65 The formulas may be varied somewhat from those given in the examples. It will be apparent that the potassium alkyl glyceryl ether sulfonate is the solubilizer for the silicate. Up to 6% silicate solids can be kept in clear solution by formulations as shown in the examples, containing alkyl glyceryl ether sulfonate and potassium pyrophosphate. There is no point in going below 3.5% silicate solids as inhibition of corrosion becomes inadequate below this point. The silicate can have a ratio of $\text{SiO}_2/\text{Na}_2\text{O}$ of 1.6 to 1 to 2.6 to 1. Lower ratios become too alkaline and higher ratios are difficult to dissolve.

The solubilizing power of alkyl glyceryl ether sulfonate is exerted upon the phosphates as well as the silicates. The potassium pyrophosphate or potassium tripolyphosphate may be used in an amount from a minimum of 12 parts to a maximum of the limit of solubility at room temperature of the phosphate in the complete detergent. This maximum limit on the amount of phosphate depends upon the amount of the second anionic used. When a heavy duty liquid detergent is prepared with alkyl glyceryl ether sulfonate as the sole anionic (and with added solubilizing agents), 30 parts of potassium pyrophosphate could be dissolved in a composition containing 50 parts of water and 12 parts of alkyl glyceryl ether sulfonate. When 4 of the 12 parts of alkyl glyceryl ether sulfonate in the above solution are replaced by 5 parts of alkyl benzene sulfonate the solubility of the potassium phosphates is reduced to about 23 parts. Our preferred phosphate is pyrophosphate because of the greater solubility and stability of this phosphate.

Coconut amides may be mono- or diethanol, propanol or isopropanol and can be tolerated from the standpoint of freeze recovery up to about 3%. Below 1% they do not accomplish much enhancement of sudsing.

The alcohols, ethanol or isopropanol, or diethylene glycol monobutyl ether, used to dissolve the amide, to reduce viscosity and to act as assistant solubilizers are preferably used from about 1% to about 6%. Alcohol promotes blending and lowers viscosity, but more than 6% causes a tendency to separation. With a longer time spent in blending, alcohol may be omitted, and a satisfactory heavy duty liquid detergent can be produced.

The sodium toluene sulfonate, benzene sulfonate or xylene sulfonate may be used between 2.5% and 9%.

The amount of alkyl glyceryl sulfonate must be at least 2% in the compositions like those shown in the examples to solubilize the silicate, that is, it will be as a minimum, $\frac{1}{7}$ of the total anionic synthetic detergent. Moreover, the minimum amount of alkyl glyceryl ether sulfonate that will prevent redeposition of soil is about 2%. The amount of alkyl glyceryl ether sulfonate may go as high as 14, but at the expense of clarity at low temperatures. The preferred range is 4% to 8%, with the second anionic being present at 9% to 5%. With the second anionic at $\frac{1}{4}$ the alkyl glyceryl ether sulfonate, the minimum amount of anionic synthetic detergent in the compositions of this invention will be $7\frac{1}{2}\%$.

Alkyl (EtO)₃ sulfate was used as the second anionic detergent in Example III. In the reaction between a high molecular alcohol and n-moles of ethylene oxide per mole of alcohol the species produced not all contain n-moles of ethylene oxide. The species will vary from $n=0$ to those wherein the polyethylene oxide is at least $2n$ in polymerization. For this reason there is nothing specific about reacting exactly 3 moles of ethylene oxide. The sulfated reaction products of 2 moles of ethylene oxide and of 4 moles of ethylene oxide with a given fatty alcohol will differ only slightly from alkyl (EtO)₃ sulfate, and may be used interchangeably. As moles of EtO increase, electrolyte compatibility decreases and chill improves.

The water will preferably be not less than about 40%, as this much is required to solubilize the ingredients. The water used will not exceed 75%, of the total composition if the product is to be called "concentrated."

Other anionic detergents than alkyl benzene sulfonate, sulfated alkyl ethylene oxide condenses, and sulfated non-ylphenol ethylene oxide condensates may be used as second anionics. The anionic sulfuric organic reaction products which are preferred are those which have sodium or potassium or substituted ammonium salts which have a solubility of at least 4 parts in 50 parts of water in which is dissolved 8 parts of potassium alkyl glyceryl ether sulfonate and 20 parts of potassium pyrophosphate with 6 parts of sodium toluene sulfonate and 4 parts of ethyl alcohol; and which do not hydrolyze in alkaline aqueous

solution. Stability in alkaline aqueous solutions is essential for every constituent.

What is claimed is:

1. A substantially clear concentrated liquid detergent composition consisting essentially of, in parts by weight: (a) $7\frac{1}{2}$ parts to 14 parts of anionic synthetic detergents of which not less than 2 parts and not more than 75% is potassium salts of alkyl glyceryl ether sulfonate, said alkyl containing at least 50% of radicals from alcohols of 10 to 14 carbon atoms, the remainder of the anionic synthetic detergent being an alkaline-stable organic sulfuric reaction product the alkali metal and alkylol amine salts of which are characterized by a solubility of at least 4 parts in a solution consisting of 8 parts of said potassium alkyl glyceryl ether sulfonate and 20 parts of potassium pyrophosphate in 50 parts of water with 6 parts of sodium toluene sulfonate and 4 parts of ethyl alcohol, said organic sulfuric reaction product being stable in aqueous alkaline solution; (b) a phosphate selected from the group consisting of potassium tripolyphosphate and potassium pyrophosphate and mixtures thereof, in an amount from a minimum of 12 parts to the limit of solubility at room temperature of said potassium phosphate in the complete detergent; (c) 3.5 parts to 6 parts of sodium silicate solids of $\text{SiO}_2/\text{Na}_2\text{O}$ ratio of 1.6:1 to (2.6:1; (d) 2.5 parts to 9 parts of an anionic solubilizer selected from the group consisting of trialkyl phosphates wherein each of the alkyl groups contains not more than 5 carbon atoms, the alkali metal salts of benzene sulfonate, the alkali metal salts of toluene sulfonate and the alkali metal salts of xylene sulfonate; (e) 40 to 75 parts of water, to bring the total of all components to 100 parts.

2. A substantially clear concentrated liquid detergent composition consisting essentially of, in parts by weight: (a) $7\frac{1}{2}$ to 14 parts of anionic synthetic detergents of which not less than 2 parts and not more than 75% is potassium salt of alkyl glyceryl ether sulfonate, said alkyl containing at least 50% of radicals from alcohols of 10 to 14 carbons, the remainder of the anionic synthetic detergent being an organic sulfuric reaction product the alkali metal and alkylol amine salts of which are characterized by a solubility of at least 4 parts in a solution of 8 parts of said potassium alkyl glyceryl ether sulfonate and 20 parts of potassium pyrophosphate in 50 parts of water with 6 parts of sodium toluene sulfonate and 4 parts of ethyl alcohol, said organic sulfuric reaction product being stable in alkaline aqueous solution; (b) a potassium phosphate selected from the group consisting of potassium tripolyphosphate and potassium pyrophosphate and mixtures thereof, from a minimum of 12 parts to the maximum of the limit of solubility at room temperature of said potassium phosphate in the complete detergent; (c) 1 to 6 parts of assistant solubilizers selected from the group consisting of ethyl alcohol, isopropyl alcohol, and diethylene glycol monobutyl ether; (d) 1.0 parts to 3.0 parts of alkylol amide of fatty acids of the coconut group, said alkylols being selected from the group consisting of monoethanol, diethanol, monoisopropanol, and di-isopropanol; (e) 3.5 parts to 6 parts of sodium silicate solids of $\text{SiO}_2/\text{Na}_2\text{O}$ ratio of 1.6:1 to 2.6:1; (f) 2.5 parts to 9 parts of an anionic solubilizer selected from the group consisting of trialkyl phosphates wherein each of the alkyl groups contains not more than 5 carbon atoms, the alkali metal salts of benzene sulfonate, the alkali metal salts of toluene sulfonate and the alkali metal salts of xylene sulfonate; (g) Water to make 100 parts but not less than about 40 parts.

3. The liquid detergent composition of claim 2 containing about 8 parts of the potassium alkyl glyceryl sulfonate; about 5 parts of the alkali metal salt of alkyl benzene sulfonate, about 20 parts of potassium pyrophosphate, about 4 parts of the alcohol, about $\frac{1}{5}$ part of the alkylol amide, about 4 parts of the sodium

silicate solids and about 4 parts of sodium toluene sulfonate, sufficient water being present to bring the total of all components to 100 parts.

4. A substantially clear concentrated liquid detergent composition consisting essentially of, in parts by weight, 2 to 9 parts of the potassium salts of alkyl glyceryl ether sulfonate, at least 50% of the alkyl groups of the said alkyl glyceryl ether sulfonate being derived from alcohols having from 10 to 14 carbon atoms, 4 to 9 parts of alkali metal alkyl benzene sulfonate, the alkyl group of which averages about 12 carbon atoms, the sum of the said salts of alkyl glyceryl ether sulfonate and alkali metal alkyl benzene sulfonate being not more than 14 parts, 18 to 22 parts of potassium pyrophosphate, 3 to 5 parts of ethyl alcohol, 1 to 2 parts of alkylol amides of the fatty acids derived from oils of the coconut group, the alkylol portion of the said amides being selected from the group consisting of monoethanol, diethanol, monoisopropanol and diisopropanol, 3.5 to 6 parts of sodium silicate solids having an $\text{SiO}_2/\text{Na}_2\text{O}$ ratio of from 1.6:1 to 2.6:1, 2.5 to 9 parts of sodium toluene sulfonate and not less than 40 parts of water and sufficient to bring the total of all components to 100 parts.

5. A substantially clear concentrated liquid detergent composition consisting essentially of, in parts by weight, 2 to 9 parts of the potassium salts of alkyl glyceryl ether sulfonate, at least 50% of the alkyl groups of the said alkyl glyceryl ether sulfonate being derived from alcohols having from 10 to 14 carbon atoms, 4 to 9 parts of alkali metal alkyl benzene sulfonate, the alkyl group of which averages about 12 carbon atoms, the sum of the said salts of alkyl glyceryl ether sulfonate and alkali metal alkyl benzene sulfonate being not more than 14 parts, 18 to 22 parts of potassium pyrophosphate, 3 to 5 parts of isopropyl alcohol, 1 to 2 parts of alkylol amides of the fatty acids derived from oils of the coconut group, the alkylol portion of the said amides being selected from the group consisting of monoethanol, diethanol, monoisopropanol and diisopropanol, 3.5 to 6 parts of sodium silicate solids having an $\text{SiO}_2/\text{Na}_2\text{O}$ ratio of from 1.6:1 to 2.6:1, 2.5 to 9 parts of sodium toluene sulfonate and not less than 40 parts of water and sufficient to bring the total of all components to 100 parts.

6. A substantially clear concentrated liquid detergent composition consisting essentially of, in parts by weight, 4 to 8 parts of the potassium salts of alkyl glyceryl ether sulfonates, at least 50% of the alkyl groups of the said alkyl glyceryl ether sulfonates being derived from alcohols having from 10 to 14 carbon atoms, 3.5 to 4.5 parts of the potassium salts of the sulfated reaction product of from 2 to 4 moles of ethylene oxide with 1 mole of a mixture of fatty alcohols, at least 50% of the mixture of said fatty alcohols being fatty alcohols containing from 10 to 14 carbon atoms, 18 to 22 parts of potassium pyrophosphate, 4 to 5 parts of ethyl alcohol, 1.5 to 2.5 parts of alkylol amides of the fatty acids derived from oils of the coconut group, the alkylol portion of the said amides being selected from the group consisting of monoethanol,

5 diethanol, monoisopropanol and diisopropanol, 3 to 5 parts of sodium silicate solids having an $\text{SiO}_2/\text{Na}_2\text{O}$ ratio of from 1.6:1 to 2.6:1, 5 to 8 parts of sodium toluene sulfonate and not less than 50 parts of water and sufficient to bring the total of all components to 100 parts.

7. A substantially clear concentrated liquid detergent composition consisting essentially of, in parts by weight, 4 to 8 parts of the potassium salts of alkyl glyceryl ether sulfonates, at least 50% of the alkyl groups of the said alkyl glyceryl ether sulfonate being derived from alcohols having from 10 to 14 carbon atoms, 3.5 to 4.5 parts of the potassium salts of the sulfated reaction product of from 2 to 4 moles of ethylene oxide with 1 mole of a mixture of fatty alcohols, at least 50% of the mixture of said fatty alcohols being fatty alcohols containing from 10 to 14 carbon atoms, 18 to 22 parts of potassium pyrophosphate, 4 to 5 parts of isopropyl alcohol, 1.5 to 2.5 parts of alkylol amides of the fatty acids derived from oils of the coconut group, the alkylol portion of the said amides being selected from the group consisting of monoethanol, diethanol, monoisopropanol and diisopropanol, 3 to 5 parts of sodium silicate solids having an $\text{SiO}_2/\text{Na}_2\text{O}$ ratio of from 1.6:1 to 2.6:1, 5 to 8 parts of sodium toluene sulfonate and not less than 50 parts of water and sufficient to bring the total of all components to 100 parts.

8. A substantially clear concentrated liquid detergent composition consisting essentially of, in parts by weight, 8 parts of the potassium salts of alkyl glyceryl ether sulfonate, at least 50% of the alkyl groups of the said alkyl glyceryl ether sulfonate being derived from alcohols having from 10 to 14 carbon atoms, 4 parts of the potassium salts of the sulfated reaction product of 3 moles of ethylene oxide with 1 mole of a mixture of fatty alcohols, at least 50% of said mixture of fatty alcohols being fatty alcohols containing from 10 to 14 carbon atoms, 20 parts of potassium pyrophosphate, 4 parts of ethyl alcohol, 4 parts of sodium silicate solids having a $\text{SiO}_2/\text{Na}_2\text{O}$ ratio of 1.6:1 to 2.6:1, 1.5 to 2.5 parts of alkylol amides of the fatty acids derived from oils of the coconut group, the alkylol portion of the said amides being selected from the group consisting of monoethanol, diethanol, monoisopropanol and diisopropanol, 6 parts of sodium toluene sulfonate and water in an amount sufficient to bring the total of all components to 100 parts.
